UNITED STATES PATENT OFFICE.

JOSHUA W. HOUCHEIN AND JOSHUA R. HOUCHEIN, OF BROOKLYN, NEW YORK.

GLASS-FURNACE.

SPECIFICATION forming part of Letters Patent No. 254,653, dated March 7, 1882.

Application filed July 20, 1881. (No model.)

To all whom it may concern:

Be it known that we, JOSHUA W. HOUCHEIN and JOSHUA R. HOUCHEIN, of Brooklyn, in the county of Kings and State of New York, have 5 invented a new and useful Improvement in Glass-Furnaces, of which the following is a specification.

Our present invention relates to ordinary glass-furnaces in which the material to be 10 melted is deposited in a series of melting-pots placed at suitable distances apart on the floor of one common furnace.

The object of the invention is to so improve the construction of similar furnaces as to adapt 15 them for burning petroleum or other liquid hydrocarbon, the combustion being aided and the heat intensified by an adjustable auxiliary air-blast superjacent to the hydrocarbon nozzle, as in the furnace heretofore invented by 20 us for puddling and smelting iron.

The invention consists in the construction and combination of parts arranged as herein-after described and claimed.

In the accompanying two sheets of drawings, 25 Figure 1 represents a longitudinal vertical section of our improved glass-melting furnace, the section being taken on the line $x-x$ of Fig. 2. Fig. 2 is a horizontal section of the same, taken through the line $y-y$ of Fig. 1. Fig. 3 is a vertical cross-section of the same, taken through the line $z-z$ of Fig. 1, and seen in direction of the arrow. Fig. 4 is a vertical cross-section of the same, taken through the line $v-v$ of Fig. 1, and seen in direction of the arrow.

30 Like letters of reference indicate like parts in the several figures.

A designates the furnace proper, on the floor a of which four melting-pots, B, are arranged, as shown. The roof of the furnace is elliptic 40 in cross-section, as represented in Figs. 1 and 3, and the walls are rounded off, as shown in Fig. 2, allowing of two openings, a' , for each pot to be arranged in the wall, through which the melted glass is accessible by the blowing- 45 pipe. These openings a' are of course closed while the glass is being melted. The front of the furnace proper, A, is limited by a vertical wall, C, through which a tapering flue, c , (whose bottom is above the upper level of the melting-

pots B, and whose top forms an extension of 50 the inside of the furnace-roof,) extends to the mouth of the adjustable superjacent air-jet nozzle D. This is constructed as described in our previous patent application, with the exception that it has double walls, forming 55 between them a shallow chamber, d , through which a stream of water is circulated by the pipes d' , to keep the nozzle cool enough to prevent its destruction by heat.

Below the mouth of the nozzle D is the kindling-box E, near whose bottom the petroleum-pipe F and its atomizing air-pipe G enter. The fire-bridge H is provided with a horizontal air-passage, h , for cooling it. The kindling-box E is accessible through a side hole, which is closed 65 by a tightly-fitting tapering block, e , removable by means of a suitable handle, e' .

Below the level of the furnace-floor is arranged a rectangular prismatic blast heating chamber, I, extending from the wall C to a considerable distance beyond the outer front wall of the furnace, and terminating with a flue, J, which leads to the chimney. The rear end of the chamber I is connected with the furnace proper, A, by a central downward flue, i , issuing through the wall C just above the floor a . In the chamber I is placed the blast-pipe K, arranged in several coils or return-bends, as shown, so as to expose a large heating-surface to the action of the air from the furnace. From 75 its coiled portion the pipe K extends upward, gradually widening toward the nozzle D, in joining which it assumes the full width of the flue e , a portion of its air being first led off by the branch pipe G to atomize the liquid fuel 80 issuing from the pipe F. The air-current created by a revolving fan or other blowing apparatus passes through the pipe K in direction of arrow 1, and after discharging a branch current through the pipe G, to vaporize the liquid fuel 85 into the kindling-box E, issues through the nozzle D and flue e , the jet gradually widening as it enters to the full width of the furnace A. Passing the fire-bridge H it intercepts the yet 90 smoky vapors from the kindling-box, causing their perfect combustion, and whirling them at intense heat over and around the melting-pots B to the extreme rear end of the furnace 95

A, whence they recoil, whirling around the lower parts of the pots until they reach and escape through the opening *i* to the chamber I, where they heat the pipe K and the blast, 5 and finally escape by the flue J to the chimney. The gases, after melting the glass, thus heat the blast, and then escape by the flue J to the chimney at the same end of the furnace at which they entered it.

10 Having thus described our invention, what we claim as new, and desire to secure by Letters Patent, is—

15 1. A glass-furnace having in connection with a liquid-fuel atomizer, G F, and superjacent air-blast nozzle D, a narrow tapering fire-flue, *e*, gradually increasing in width and depth as it enters the wider furnace proper, A, the latter being provided with rounded corners, allowing of two working-openings for each melting-pot, substantially as specified.

20 2. In a glass-melting furnace provided with a liquid-fuel atomizer, G F, and superjacent air-blast nozzle D, the tapering blast and fire

flue *e*, widening into the upper part of the furnace proper, A, in combination with the return-flue *i*, issuing through the wall C at the furnace-floor, the oblong heating-chamber I, terminating into the chimney-flue J, and the coiled blast-pipe K, placed in the said chamber and leading thence up to the said nozzles, 25 30 all constructed and arranged substantially as shown and set forth.

3. In a glass-melting furnace using liquid-hydrocarbon fuel, the upper blast and fire-entering flue, *e*, and the lower returning discharge-flue, *i*, both arranged in the front wall, C, of the furnace proper, A, in combination with the heating-chamber I, the coiled blast-pipe K, the atomizing-nozzle G F, and the superjacent air-blast nozzle D, substantially as specified.
